Inventor.

E.W.Rutherford,

By his Attorney.

Brent Hopkins

UNITED STATES PATENT OFFICE.

EUGENE W. RUTHERFORD, OF NEW HAVEN, CONNECTICUT, ASSIGNOR TO THE SHOE HARDWARE COMPANY, A CORPORATION OF CONNECTICUT.

BUCKLE.

1,346,979.

Specification of Letters Patent. Patented July 20, 1920.

Application filed January 10, 1919, Serial No. 270,461. Renewed June 5, 1920. Serial No. 386,925.

To all whom it may concern:

Be it known that I, EUGENE W. RUTHERFORD, a citizen of the United States, and a resident of New Haven, county of New Haven, and State of Connecticut, have invented certain new and useful Improvements in Buckles, of which the following is a full, clear, and exact description.

This invention relates to buckles and more particularly to buckles of the type embodying a plate member to which is pivoted a locking tongue adapted to be thrown open to receive an eye member and to be closed to retain the same.

There have heretofore been used upon boots, shoes, arctics, and various other articles, buckles formed of two stampings of sheet metal, and comprising a socketed plate member to which is hingedly secured a hook-shaped locking tongue having pintles which seat in the sockets in the plate member. The plate member of such buckles is customarily formed at one end with three extensions or fingers suitably spaced apart, the outer two extensions being provided with alined sockets which receive the pintles of the locking tongue. The intermediately disposed extension acts as a spring and cooperates with a cam surface on the locking tongue to hold the tongue in opened and closed positions. The sockets in the two outer extensions are formed by striking up a portion of the metal intermediate the length of the extensions and bending back the ends of the extensions to overlie the recesses so formed. It has been found that the pintle pins of the locking tongue and the bent over ends of the socketed extensions frequently break off under the strains encountered in service destroying the value of the buckle. A further disadvantage of such buckles is the high cost of manufacture involved in shaping the two members to their complicated form.

An object of the present invention, accordingly, is to provide a buckle of simple construction and great durability, which can be produced at a very low cost of manufacture.

With this and other objects in view which will hereinafter more readily appear, the invention consists in the novel construction, combination and arrangement of parts hereinafter more fully described and claimed.

A practical embodiment of the invention

is represented in the accompanying drawings forming a part of this specification, in which similar characters of reference indicate corresponding parts in all the views.

Figure 1 is a plan view illustrating the buckle with its locking tongue in closed position.

Fig. 2 is a side view of the buckle shown in Fig. 1, the locking tongue being shown in closed position in full lines and in open position in dotted lines.

Fig. 3 is a bottom view of the buckle shown in Fig. 1, and

Fig. 4 is a front end view of the construction shown in Fig. 1.

The buckle illustrated in the drawings comprises a flat plate member 10 to which is secured a hook-shaped locking tongue 11. Preferably both parts are stamped from resilient sheet steel, although it is to be understood that any suitable kind or grade of sheet metal may be employed for the purpose.

The plate member 10 is formed at one end with two eyes 12 which afford a convenient means for attaching the buckle to any desired article; and at the other end with three spaced extensions or fingers. The two outer extensions 13 are formed with bent-over ends 14, while the intermediate extension 15 is formed with a hook-shaped bend 16 which serves as a socket to hingedly secure the locking tongue to the plate member.

The locking tongue 11 consists of a substantially triangular shaped piece of metal bent at one end to resemble a hook. The hook end of the tongue is formed with a laterally extending slot 17 to provide a pintle bar 18 adapted to fit in the socket in the intermediate extension. The tongue is made of sufficient width to provide a cam shoulder 19 on each side of the slot. When the parts are assembled the cam shoulders fulcrum upon the outer extensions 13 of the plate member, and coöperate with the resilient intermediate extension 15 to hold the tongue in open and closed positions.

The invention provides a buckle of great durability and simple construction which can be more economically manufactured than any of the buckles heretofore known.

While I have described one of the preferred embodiments of my invention, it is to be understood that various modifications in

form, material and arrangement may be made without departing from the spirit and scope, or sacrificing any of the advantages of the invention defined in the appended 5 claims.

Having thus described my invention, what I claim and desire to protect by Letters Patent is:

1. A buckle comprising a plate with 10 spaced side members between which is sustained a resilient member that is bent at its free end, a manipulable tongue provided with a transversely extending elongated opening adjacent one end thereof adapted to 15 receive the bent end of the resilient member, and coöperating means on said plate and tongue for holding the latter yieldingly against the former.

2. A buckle comprising a plate with 20 spaced side members between which is sustained a resilient member that is bent at its free end, a manipulable tongue provided with a transversely extending elongated opening adjacent one end thereof adapted to 25 receive the bent end of the resilient member, said tongue having shoulders on its opposite sides beyond the elongated opening coöperating with the plate at opposite sides of the resilient member.

3. A buckle comprising a plate with 30 spaced flat side members, an intermediate resilient member having a free end which is bent into substantially semi-circular form, and a manipulable tongue provided transversely with a closed slot adjacent one end 35 which is adapted to receive the bent free end of the resilient member, said tongue having a straight edge adjacent and parallel with the slot which is adapted to coöperate with the flat side members of the plate to retain 40 the tongue in either a closed or an open position.

4. A buckle comprising a base member, a resilient member sustained at one end by the base member and free at its other end, a 45 manipulable tongue having a transverse slot adjacent one of its ends adapted to receive the free end of the resilient member and thereby hingedly supported, and means on the tongue adjacent the slot coöoperating 50 with the base member to spring the resilient member whereby the tongue may be pressed yieldingly toward the base member or may be swung away from the same.

Signed at Waterbury, county of New 55 Haven, State of Connecticut, this 2d day of January, 1919.

EUGENE W. RUTHERFORD.
